UNITED STATES PATENT OFFICE.

ERLE K. BAKER, OF CHICAGO, ILLINOIS, ASSIGNOR TO UNIVERSAL RIM COMPANY, OF CHICAGO, ILLINOIS, A CORPORATION OF ILLINOIS.

METALLIC VEHICLE-WHEEL.

1,199,859.

Specification of Letters Patent.

Patented Oct. 3, 1916.

Application filed November 26, 1912. Serial No. 733,673.

To all whom it may concern:

Be it known that I, ERLE K. BAKER, a citizen of the United States, and a resident of Chicago, Cook county, Illinois, have invented certain new and useful Improvements in Metallic Vehicle-Wheels, of which the following is a specification.

My invention relates to improvements in vehicle wheels and has particular reference 10 to improvements in wheels of the demountable rim type.

The object of my invention is to provide a metallic vehicle wheel which shall be particularly adapted for being manufactured 15 at a relatively low cost; which shall be light in weight; and which shall have ample strength to resist the severe strains to which such wheels are subjected in use.

A further object of my invention is to provide 20 a metallic wheel proper of the suspension hub type and a complementary demountable tire rim, adapted to coöperate to provide a tire mounting which shall have all the desirable qualities of wheels of this 25 character and added thereto shall be, relatively light, very strong and durable and easily manipulated both in mounting and demounting rims and tires.

My invention consists in a metallic wheel 30 proper of the suspension hub type provided with a sheet metal fixed rim, and a complementary demountable tire-rib, in combination with means for bracing and retaining the fixed rim in its normal shape and condition 35 and preventing its distortion by the strains incident to its use.

My invention further consists in a metallic vehicle wheel provided with a U-shaped hollow fixed rim adapted to receive and to 40 retain a demountable tire rim and having brace members within the fixed rim rigidly retaining the walls of the fixed rim in proper spaced relation.

My invention also consists in the several 45 combinations and arrangements of parts and in the various features of construction, whereby the above mentioned and other objects are attained and all as hereinafter described and particularly pointed out in the 50 appended claims.

My invention will be more readily un-

derstood by reference to the accompanying drawings in which:

Figure 1 is a side elevation of a pneumatic tired automobile wheel of the suspension hub type, embodying my invention in one form; Fig. 2 is an enlarged transverse section of the rim part of the wheel on the line 2—2 of Fig. 1, particularly illustrating one of the rim-clamping devices; Fig. 3 is 60 a section similar to Fig. 2, but taken on the line 3—3 of Fig. 1 through one of the rim-supporting braces; Fig. 4 is a circumferential central section of the demountable rim and fixed rim on the line 4—4 of Fig. 3; Fig. 5 is an enlarged circumferential section on the line 5—5 of Fig. 1, particularly illustrating the spacing struts in combination with the clamping bolt; Fig. 6 is an inner plan view 70 of the tire rim showing the split therein and the means connecting its ends; Fig. 7 is a perspective view of one of the spacers shown in section in Fig. 3; Figs. 8 and 9 are cross sectional views of modified forms of rim sections; Fig. 10 is a view similar to 75 Fig. 2 showing a combined form of fixed rim brace and rim clamping device; Fig. 11 is a view similar to Fig. 10 showing another modified form of combined fixed rim brace and rim clamping device; Fig. 12 is a plan 80 view showing another modification of the combined fixed rim brace and rim clamp; Fig. 13 is an elevation of a portion of the rear face of the fixed rim showing the device illustrated in Fig. 12; Fig. 14 is a view 85 similar to Fig. 10 showing another modified form of fixed rim brace and rim clamping device; Fig. 15 is a similar view showing another modified form of fixed rim brace and rim-clamping device; and Fig. 16 is an 90 elevation of a portion of the rear face of the fixed rim showing the device illustrated in Fig. 15.

While I have described my device as being particularly applicable to metallic 95 wheels of the suspension hub type, it should be understood that it refers more particularly to the metallic fixed rim of such wheels and to means for securing a demountable rim thereon.

The apparent desire of both manufacturers and users to eliminate wood entirely

from the construction of automobiles has led to the attempt, by many inventors, to produce metallic wheels particularly adapted for use with pneumatic and similar tires. The results attained thus far, however, have not been eminently satisfactory on account of the complication and expense of the metallic wheels and their consequent extreme high cost to the user.

- 10 It is one of the principal objects of my invention to provide a construction by means of which the cost can be reduced so that the metallic wheels can be as far as their expense is concerned at least interchangeably used with wheels constructed partly of wood, and it is further my desire to produce a metallic wheel which can be manufactured at such a low cost and which would prove itself so eminently satisfactory in use that it 15 would serve to completely eliminate wooden wheels from this field.

In my wheel, as illustrated in the drawings, I provide a hollow, U-shaped fixed rim A, opening outward. This fixed rim is suitably connected with a metallic hub B by means of a plurality of metallic or wire spokes C. The fixed rim is adapted to receive and to retain a pneumatic tire rim D which carries a suitable pneumatic tire E. 20 As illustrated in Figs. 2 and 3, the member A is a U-shaped annular channel. The base or inner wall a¹ is slightly crescent-shaped and thereby simulates the appearance of a wooden felly and is provided with suitable 25 openings a² to receive the spoke nuts c¹. The front wall a³ extends outwardly from the base and I preferably provide it at its outer edge with an inwardly turned circumferential flange a⁴. This flange serves to 30 stiffen the member and it also provides a suitable supporting or bearing surface for the rim-clamping lugs. The rear wall a⁵ of the fixed rim extends radially outwardly 35 parallel with the front wall and it terminates at its outer edge in an outwardly inclined circumferential flange a⁶ adapted to provide a circumferential seat for the tire rim D.

In order to retain the tire rim upon the 40 fixed rim, I provide a number of rim-clamping devices F, which devices carry rim clamps f¹ adapted to coöperate with the circumferential flange a⁶ to hold the tire rim D upon the wheel. As clearly shown in Fig. 2 45 each rim clamping device comprises a bolt f² mounted transversely in the fixed rim adjacent to the outer periphery or open side thereof and coöperating with a clamping nut f³ secured to or upon the rear wall of the fixed rim. The rim clamp f¹ is mounted upon the bolt f² immediately beneath the head f⁴ thereof and the bolt is provided with a circumferential shoulder f⁵ spaced 50 from the head sufficiently to admit the shank f⁶ of the clamp between them. This con-

struction provides a device by means of which the wedging clamp f¹ can be forced into clamping condition with its wedging point f⁷ between the fixed rim and the demountable rim, and it can also be operated 70 to positively withdraw the wedging clamp from its wedging position when it is desired to release the demountable rim. The nut f³ is provided with an upwardly extending shoulder or abutment f⁸ at its outer side 75 which is adapted to contact with the outer surface of the flange a⁶ and serves to support the flange a⁶ at this point. The nut f³ is also provided with laterally extending flanges f⁹ by means of which the nut is secured to the 80 fixed rim. I secure the nut to the fixed rim by means of rivets f¹⁰ and in order to brace the walls of the fixed rim and hold them in their proper spaced relation one to the other I extend the rivets f¹⁰ transversely through 85 the fixed rim and they serve to tie the front and the rear walls thereof together and prevent their separation. To rigidly hold the walls spaced apart and thus prevent them from approaching each other, I provide a 90 suitable spacer or brace which is arranged transversely between the walls and is of a suitable length to contact with both of the walls and hold them properly spaced. In the form of the invention illustrated in Figs. 95 1 to 5, inclusive, these spacers comprise spacer tubes f¹¹ placed upon and held in position by the rivets f¹⁰. These tubes extend from the rear to the front wall and when in place not only serve to hold the 100 walls in proper spaced relation, but serve as abutments to hold the walls properly spaced while the rivets f¹⁰ are being secured in position.

It will now be clear that any force transmitted to the nut f³ through the bolt f² when operating either to secure or hold the rim in position, or to loosen the wedge from its clamping position cannot serve to distort the walls of the fixed rim as the walls are rigidly braced and held in proper spaced 105 relation.

In the form of my invention illustrated in Figs. 1 to 7, I have shown the tire rim as 110 being split or cut apart at one point d¹ in its circumference, providing the rim with two ends d² and d³ for the purpose of facilitating the mounting and demounting of the rim upon the tire E. Each end of the rim 115 is provided with two circumferentially spaced inwardly extending projections or pins d⁴ rigidly mounted in the rim and serving to coöperate with a connector plate d⁵ which is provided with suitable openings d⁶ to receive the pins d⁴. This connector plate bridges the gap or cut d¹ of the rim 120 and serves to dowel and connect the two ends of the rim together. One end of the rim is provided with an opening d⁷ to receive the valve e¹ of the tire E, and the con- 125

necter d^6 is also provided with a valve stem hole and I also provide the base a^1 of the fixed rim with a suitable centrally-arranged valve-stem opening a^7 . In order to properly support the rim adjacent to the valve I provide two circumferentially spaced bridges or strut members d^7 which extend transversely across the fixed rim and are circumferentially spaced apart to coöperate with the projections d^4 of the rim, so that one strut member is arranged at each end of the rim and between the two projections d^4 thereof. I retain each of these strut members in its position by means of a rivet d^8 which extends transversely through the fixed rim and through suitable openings in the front and rear walls thereof. The outer surface d^9 of each strut member d^7 lies flush with the open top of the fixed rim and they serve as supports for the connecting plate d^5 . The strut members being received between the pairs of projections, serve to prevent relative circumferential movement between the rim and the fixed rim and thus serve to retain the demountable rim circumferentially in its proper position. In order to hold the strut members d^7 from rotating upon their securing rivets at times when they are not held by the contact with the connector plate, I provide each of these strut members with laterally extending arms or projections d^{10} at one end which extend circumferentially beneath the inwardly extending flange a^4 and thus serve to prevent the rotation of the strut upon the rivet in either direction. It will now be seen that the walls of the fixed rim are rigidly braced at many points around its circumference and consequently the fixed rim is retained in its true and normal shape and is prevented from being distorted by the severe strains to which it is subjected in use, not only in consequence of the strains and shocks which it receives when running over rough roads, but also from the strains incident to the clamping and loosening of the rim by means of the rim clamping bolts.

In some instances I find it advisable instead of arranging the flange a^4 projecting inwardly toward the plane of the wheel to turn it outwardly, as illustrated in Fig. 8, the flange in this instance serving to stiffen the wall a^8 of the fixed rim similar to its use in the form of rim illustrated in Figs. 2 and 3. In some instances, however, I find that it is advisable not to use the flange a^4 at all, but to simply form up the fixed rim with a non-flanged front wall as illustrated in Fig. 9. This form of rim can be made considerably cheaper than the flanged form and for some purposes, particularly on light cars, the lessened cost is a desirable feature.

Under some conditions I prefer to do away with the transverse rivets f^{10} and their strut tubes f^{11} and in such cases I hold the

walls properly spaced apart by spacers which are combined with the clamping bolts. I have illustrated several of these forms which are desirable to use under different circumstances. One particularly advantageous form is that illustrated in Fig. 10 wherein I use a bolt h^1 which extends transversely through the fixed rim and is provided with a head h^2 adapted to contact with the rear face of the fixed rim and hold the bolt against the action of the nut h^3 mounted upon its forward end. The bolt in this instance is held in position by means of a thin nut h^4 which is screwed upon the threaded end of the bolt in advance of the clamp f^1 . By means of this nut h^4 I am enabled to clamp the bolt in the fixed rim independent of the main clamping nut h^3 and to prevent the collapsing of the walls toward each other I provide a sleeve strut h^5 which is placed upon the shank of the bolt as the bolt is placed in position. This strut contacts with the front and rear walls and serves to keep them properly spaced.

In the clamping device illustrated in Fig. 11, the bolt j^1 is similar to the bolt h^1 in Fig. 10 in that it extends through the fixed rim from the rear, but instead of being held in place by a thin nut on its threaded end it is held in place by the rivet j^2 which secures the head of the bolt to the rear wall. Similar to the device shown in Fig. 10 I here use a spacer in the form of a tube j^3 on the body of the bolt and long enough to hold the walls properly spaced apart and the bolt and spacer together serve to hold the walls against distortion.

In the clamping device illustrated in Figs. 12 and 13, the clamping bolt k^1 is similar to the bolt shown in Figs. 10 and 11, but differs therefrom by being provided on its head k^2 with laterally extending flanges k^3 , and I secure the bolt to the rear wall by means of rivets k^4 which pass through the flanges and the rear wall. In this case I provide a spacing tube k^5 on the body of the bolt similar to the spacers shown in Figs. 10, and 11.

In Fig. 14 I have illustrated another modified form of the combined rim clamp and wall spacer. In this case the bolt m^1 is similar to the bolt shown as the preferred form of device in Fig. 2, but in this case I combine the spacer with the nut and the nut m^2 , instead of extending but a short distance into the body of the fixed rim from the rear wall, extends clear across said rim and abuts on the inner face of the front wall and I secure the nut by rivets which extend through lateral flanges similar to the method of securing the nut in the form shown in Figs. 12 and 13. The bolt in this instance is provided with a withdrawing shoulder m^3 similar to the withdrawing shoulder provided on the preferred form of the bolt.

In Figs. 15 and 16 I have illustrated still

another form of combined fixed rim bracing and rim clamping device. In this form I use a bolt n^1 , similar to the bolt shown in the preferred form except that it is considerably shorter. The nut n^2 itself is placed entirely within the hollow fixed rim and extends from the rear to the front wall serving as a strut brace within the fixed rim to prevent its walls from approaching each other. The rear end of the nut is provided with laterally extending flanges n^3 and I secure the nut to the rear wall by rivets n^4 which pass through these flanges and said rear wall. The nut n^2 is provided with a centrally threaded portion n^5 to receive the threaded end n^6 of the bolt n^1 .

All of these various forms of combined fixed rim bracing and rim-clamping devices include the idea of rigidly spacing the front and rear walls of the hollow fixed rim so that the same will not be distorted by the strains transmitted through the clamping bolt and further as the fixed rim is provided with a number of these devices spaced at short intervals, its walls are rigidly held in normal, true condition.

It will now be understood that I have provided a construction which results in a strong, rigid and relatively light wheel and one which can be manufactured at a reasonably low cost and while it is particularly adapted for receiving and holding a split rim of the form illustrated, it is evident that non-split rims can be held upon the fixed rim as securely and rigidly as split rims.

As many other modifications of my invention will readily suggest themselves to one skilled in the art, I do not limit or confine my invention to the specific structures herein shown and described.

Having thus described my invention, I claim as new and desire to secure by Letters Patent:

1. In a metallic vehicle wheel of the suspension hub type a hollow-U-shaped fixed rim having its sides substantially parallel and projecting outwardly, one of said sides terminating in an outwardly inclined tire-rim receiving flange, a plurality of nuts circumferentially spaced around the fixed rim on one side, each thereof having a threaded bolt hole, a transverse clamping bolt in each, a rim clamp carried by each bolt adapted to hold a tire rim in position upon the fixed rim and against its rim-receiving flange, and spacing members arranged adjacent to each bolt within the fixed rim adapted to oppose the bolting strains and retain the sides of the fixed rim in proper spaced relation.

2. In a metallic vehicle wheel a U-shaped fixed rim having its side walls extending outwardly and being open at its outer periphery, a nut arranged against the outer face of the rear wall of the fixed rim, a rim

clamping bolt entering the nut from the opposite side of the fixed rim, rivets extending transversely through the fixed rim securing the nut in place thereon and holding the walls of the fixed rim from spreading, and strut members on said rivets within the fixed rim and spacing the walls thereof

3. In a metallic vehicle wheel of the suspension hub type, a U-shaped fixed rim having its side walls extending outwardly and open at its outer periphery, a plurality of rim clamping bolts circumferentially spaced around and transversely mounted in the fixed rim, rivets passing transversely through the fixed rim at each side of each bolt, and strut sleeves on said rivets bracing the sides of the fixed rim in opposition to the distorting action of the operative strains of the bolt.

4. In a metallic vehicle wheel a U-shaped fixed rim having its open side at its outer periphery, in combination with a demountable rim adapted to be carried by said fixed rim, threaded nuts carried on one wall of said fixed rim and clamping bolts projecting through the opposite wall of the fixed rim and coöperating with the said nuts, wedging clamps mounted between shoulders on the bolts and adapted to secure the rim on the fixed rim, the bolts being adapted to both insert and withdraw the wedges, tie rods passing through the fixed rim adjacent to each bolt and holding the sides of the fixed rim against separation when the bolt is operated to withdraw the wedge, and spacers within the fixed rim adjacent to each tie rod adapted to hold the walls of the fixed rim in spaced relation against the clamping action of the bolt.

5. In a metallic vehicle wheel a hollow, U-shaped fixed rim having its open side turned outwardly and one of its side walls provided with an outwardly inclined circumferential flange, a clamping nut carried by the flanged wall of the fixed rim adjacent to the outer periphery of the fixed rim, a rim clamping bolt extending transversely through the fixed rim and coöperating with the nut to clamp a demountable rim against the flange, and two strut members, one at each side of the bolt, and circumferentially spaced therefrom, each said member comprising a tie rod extending through the fixed rim, and a spacing sleeve on the tie rod, said sleeve contacting with the walls of the fixed rim and coöperating with the tie rod to retain the walls of the fixed rim in proper spaced relation.

6. In a metallic wheel having a U-shaped fixed rim with its open side at its outer periphery and its rear wall terminating in an outwardly inclined tire rim receiving flange, a nut fixed to the rear wall of the fixed rim and having a flange adapted to

contact with the rear face thereof, a rim clamping bolt extending through the fixed rim from the opposite side and coöoperating with the nut to retain a rim upon the fixed 5 rim, and against the flange, a tie rod extending transversely through the flange of the nut and serving to secure the nut upon the fixed rim and to prevent the walls of the fixed rim from spreading apart, and a 10 sleeve spacer on each rod within the fixed rim preventing the collapse of the fixed rim.

7. In a metallic vehicle wheel of the demountable rim type an open-topped U-shaped fixed rim adapted to receive and 15 retain a rim, said fixed rim having a circumferential tire receiving flange at one edge and having its other edge turned inwardly to form a circumferential flange, fixed rim wall spacing members arranged 20 adjacent to the periphery of the fixed rim and each having a substantially flat surface lying in the outer periphery of the fixed rim, a rivet extending transversely through the fixed rim and through each of the

spacers, and adapted to coöperate with the 25 spacer to retain the walls of the fixed rim in proper relation, and lateral wings on each of said spacers adapted to contact with the inner surface of the inwardly turned flange to hold the spacer with its flat surface in the periphery of the fixed rim.

8. In a metallic wheel for demountable rims, a fixed rim of U-shaped cross section, opening outwardly, in combination with demountable-rim clamping devices spaced 35 about said fixed rim, and means spaced within the fixed rim and fixing the distance between the walls thereof against the action of said devices, and including a rim driver.

In testimony whereof, I have hereunto 40 set my hand, this 23rd day of November, 1912, in the presence of two subscribing witnesses.

ERLE K. BAKER.
